UNITED STATES PATENT OFFICE.

MANSFIELD C. CRAWLEY, OF RUTHERFORD, NEW JERSEY, ASSIGNOR TO ADDOGRAPH COMPANY, OF LOS ANGELES, CALIFORNIA, A CORPORATION OF CALIFORNIA.

TYPEWRITING MACHINE.

Application filed June 29, 1918, Serial No. 242,511. Renewed July 14, 1922. Serial No. 574,981.

To all whom it may concern:

Be it known that I, MANSFIELD C. CRAWLEY, a citizen of the United States, and resident of Rutherford, county of Bergen, and 5 State of New Jersey, have invented certain new and useful Improvements in Typewriting Machines, of which the following is a specification.

This invention relates to improvements in 10 typewriting machines, and more particularly to means for moving the platen carriage to and arresting it at predetermined points.

One of the objects of the invention is to 15 provide tabulating mechanism embodying column selecting stops and adjustable tabulator stops, and denominational selecting means adapted to cooperate with either set of stops.

Another object of the present invention is 20 to provide tabulating mechanism embodying a denominational selector traveling with the platen carriage, adjustable tabulator stops and column selecting stops normally out of the path of the denominational selector, and independent key - controlled means for shifting the stops whereby either a selected column stop or the series of tabulating stops may be moved into the path of the denominational selector.

30 A further object is to provide a denominational selector traveling with the platen carriage, key-operated means for shifting the selector relatively to the carriage, adjustable tabulator stops and column selecting stops 35 mounted on the frame of the machine, and means whereby the selector may cooperate with either set of stops at will.

Another object is to provide tabulating mechanism embodying a carriage-arresting 40 stop, denominational selecting means, column selecting stops adapted to cooperate with the denominational selecting means, and means operable through the instrumentality of the denominational selecting means 45 for actuating the carriage-arresting stop.

Another object of the invention is to provide tabulating mechanism embodying a carriage-arresting stop, a denominational selector, adjustable tabulator stops, and connections between the denominational selector 50 and the carriage-arresting stop for actuating said stop when the denominational selector engages a tabulator stop.

Another object is to provide tabulating mechanism embodying a stationary rack, a

carriage-arresting stop traveling with the platen carriage adapted to engage said rack, column-selecting stops and adjustable tabulator stops, a denominational selector traveling with the carriage, independent key-operated means for presenting either a column-selecting stop or the series of tabulator stops in the path of the selector, and connections between the selector and carriage-arresting stop for actuating the carriage-arresting 60 stop when the selector engages either a column-selecting stop or a tabulator stop.

A further important object of the invention is to provide means for arresting the platen carriage at predetermined points, embodying a carriage-arresting stop, tabulating point selecting means adapted to actuate said stop, and marginal point determining means for actuating said stop.

Another object of the invention is to provide a marginal point indicator adjustable transversely of the machine, a trip adjustable with said indicator and operable by the carriage, a carriage-arresting stop traveling with the platen carriage, and connections between said trip and stop for actuating the 70 stop.

A further important object of the invention is to provide key-controlled power mechanism for driving the platen carriage in 75 either direction of its travel to the point selected by the tabulating mechanism.

The tabulating mechanism herein shown and described has certain features in common with the tabulating mechanism forming 80 the subject matter of my co-pending application Serial No. 591,582, in which the features common to both applications are broadly claimed, the present application being subordinate to said application Serial 85 No. 591,582.

In the drawings, Fig. 1 is a vertical sectional view on the line I—I of Fig. 2;

Fig. 2 a fragmentary plan view of a typewriting machine provided with the improved 100 tabulating mechanism, the carriage and certain other parts being removed;

Fig. 3 a fragmentary horizontal section on the line III—III of Fig. 5;

Fig. 4 a fragmentary vertical transverse 105 sectional view on the line IV—IV of Fig. 5;

Fig. 5 a detail vertical section on the line V—V of Fig. 3;

Fig. 6 a detail perspective view of the carriage-arresting tabulator stop actuator;

Fig. 7 a detail perspective view of the denominational selector and its supporting and guiding member;

Fig. 8 a vertical transverse section on the 5 line VIII—VIII of Fig. 1;

Fig. 9 a fragmentary detail perspective view of the marginal-point indicator and its associated carriage-stop-actuating trip device;

10 Fig. 10 a fragmentary vertical transverse section on the line X—X of Fig. 1; and

Figs. 11 and 12 detail horizontal and vertical sectional views, respectively, showing parts of the carriage releasing and driving 15 means.

The tabulating and margin stop mechanism illustrated is shown embodied in a power-operated typewriting machine of the type disclosed in my Patent No. 1,455,112, 20 dated May 15, 1923, and my co-pending application Serial No. 188,770, filed August 29, 1917, and in which the platen carriage is adapted to be driven in either direction by key-controlled power mechanism such as dis- 25 closed in my co-pending application Serial No. 188,772, filed August 29, 1917. It will be obvious, however, that the tabulating and margin stop mechanism may be employed in connection with other forms of power-operated typewriting machines, as well as with 30 machines which are not power driven, and also that the tabulating and margin stop mechanism may be employed in connection with machines having any form of carriage 35 feed and in which the carriage is returned by hand or otherwise.

Referring to the various parts by numerals, 1 designates the drive shaft which is continuously rotated by means of a suitable 40 electric motor connected by belt 2 with a driving pulley 3 fixed on the drive shaft. The drive shaft 1 is journaled in bearings 4 on the frame of the machine. Loosely mounted on the drive shaft between spaced 45 collars are two oppositely beveled gears 5 and 6. Keyed to the drive shaft 1 between said gears is a shiftable clutch head 7, which is provided at its opposite ends with clutch members 8 and 9 provided on their outer 50 faces with frustro-conical clutch surfaces which are adapted to engage corresponding surfaces formed on the inner faces of the beveled gears 5 and 6. Engaging the gears 5 and 6 is a beveled pinion 10 fixed to the 55 lower end of a vertical carriage driving shaft 11. On the upper end of the shaft 11 is fixed a carriage driving pinion 12 meshing with the carriage feed rack 13. The feeding mechanism, which operates through the 60 driving pinion 12, is not shown herein, as that mechanism is fully disclosed in my aforesaid co-pending application Serial No. 188,770.

The clutch head 7 is adapted to be shifted 65 in opposite directions through mechanism

controlled by two key-operated levers 14 and 14^a pivotally supported intermediate their ends on a transversely extending pivot bar 14^b suitably supported in the frame of the machine. The rear end of lever 14^a engages the substantially horizontal arm of a bell-crank lever 15 pivoted in the main frame of the machine with its other arm extending upwardly from the pivot. Connected to this upwardly extending arm of the 70 bell-crank lever 15 is an inwardly extending substantially horizontal link 16 the inner end of which is provided with the upwardly and outwardly inclined slot 17. Pivoted in the main frame directly below the 75 carriage drive shaft 11 is a bell-crank lever 18 having a downwardly extending arm 18^a and an arm 18^b which extends horizontally transversely of the machine, substantially on a line with the pivot of the bell-crank 80 lever. The depending arm 18^a is provided with a forwardly extending horizontal pin 19 which extends through the slot 17 in the link 16. Said arm 18^a of the bell-crank lever is also provided with a stop pin 20 below the 85 pin 19, which is adapted to be engaged by a hook-like shoulder 21 formed on the lower edge of the inner end of link 16 when said link is moved laterally through the bell-crank lever 15 and the lever 14^a. In the 90 main frame directly below the clutch head 7 is pivoted a clutch shifting lever 22, the upper end of which carries a roller 23 which engages the inner surfaces of the clutch members 8 and 9, as shown more clearly in 95 Fig. 10. The lower end of the clutch shifting lever 22 is forked, and the arm 18^a of the bell-crank lever 18 is provided with a forwardly extending pin 24 which extends between the branches of the forked end of 100 said depending arm 18^a, so that the clutch shifting lever will be swung on its pivot when the bell-crank lever 18 is moved. The lever 14 engages the horizontal arm of a bell-crank lever 25, the upwardly extending 105 arm of which is connected to the outer end of an inwardly extending link 26. The link 26 is provided with a slot 27 which corresponds with slot 17 in link 16. The pin 19 extends through the slot 27 in link 26 as well 110 as through the slot 17 in link 16. The link 26 is provided at its inner end with a hook-like shoulder 28 corresponding with the shoulder 21 formed on link 16, and which is adapted to engage the stop pin 20 when the 115 lever 14 is operated.

The upwardly turned forward end of the lever 14 is pivotally connected with the lower end of a key stem 36^a on the upper 120 end of which is supported a key 36. The upwardly turned forward end of the lever 14^b is pivotally connected with the lower end of a key stem 37^a, on the upper end of which is supported a key 37. It is manifest that by depressing the key 37 the link 16 will be 125 130

5 moved inwardly by the lever 14^a, and the slot 17 in said link will guide the inner end of the link downwardly to cause the shoulder 21 to engage the stop pin 20 on the bell-
 10 crank lever 18. Further inward movement of the link 16 will then swing the bell-crank lever 18 on its pivot, causing the pin 24 to move the gear shifting lever 22 and thrust the clutch member 9 into engagement with the clutch surface on the inner face of the gear 5. It will also be obvious that by depressing the key 36 the bell-crank lever 18 will be moved in the opposite direction through the lever 14, bell-crank lever 25 and link 26, thereby bringing the clutch member 8 into engagement with the clutch surface formed on the inner face of the gear 6. It will be obvious that when the key 37 is depressed the power mechanism will be connected to drive the carriage in the direction of its return movement or toward the right-hand side of the machine, and that when the key 36 is depressed the power mechanism will drive the carriage toward the left-hand side of the machine or in the direction of its letter-spacing movement.

15 On the carriage drive shaft 11 is mounted a star detent wheel 29 which is rigidly secured to the beveled gear 10 to rotate therewith. Mounted on a suitable pivot is a detent bell-crank lever 30, one arm of which carries a roller 31 adapted to engage the teeth of the star wheel 29 to normally hold the shaft 11 against rotation. The other 20 arm of the detent lever 30 is in position to be engaged by the upper end of a release lever 32 pivotally supported on the main frame, the lower end of said lever being formed with two cam surfaces 33 and 34 25 adapted to be engaged by a roller 35 mounted on the free end of the horizontal arm 18^b of the bell-crank lever 18. It will be obvious that when the bell-crank lever 18 is swung on its pivot the release lever will 30 be moved to swing the detent lever 30 and move the roller 31 out of engagement with the teeth of the star wheel 29. The movement of the bell-crank lever in one direction will cause the roller 35 to engage the 35 cam surface 33 on the release lever, and movement of said bell-crank in the opposite direction will cause the roller 35 to engage the cam surface 34 on the release lever, so that the release lever 30 will be swung on its pivot by the operation of either one of the levers 14 or 14^a. By releasing the roller 31 from the detent wheel 29 the carriage drive shaft will be free to be driven in either direction from the drive shaft 1.

40 The platen carriage 38 is adapted to travel transversely of the frame of the machine, being supported adjacent its rear edge on suitable antifriction bearings 39 and 40. Any suitable mechanism may be provided 45 for imparting a step-by-step letter-feed

50 movement to the carriage, such as that described and shown in my copending application Serial No. 188,770, filed August 29, 1917. A stationary tabulator rack 41 is rigidly held to the frame of the machine at 55 the rear of the platen carriage 38, and a stop 42 provided with oppositely extending projections 42^a and 42^b adapted to engage between the teeth of the rack 41 is pivotally held to the carriage 38 by a screw 43. The carriage-arresting stop 42 is provided with a rearwardly extending projection 44 extending between the adjacent lower ends of two depending arms 45 and 46 formed on a carriage-arresting-stop-actuating plate 47. The 60 carriage-arresting-stop actuator 47 is mounted on the platen carriage 38 to travel therewith and is shiftable relatively to the carriage transversely of the machine. The plate 47 is held to the carriage by means of two screws 48 passing through elongated slots 49 in the plate and threaded into a part of the platen carriage. The plate 47 is normally held in the position shown in Figs. 3 and 4 by means of two coil springs 50.

65 A denominational selector 51 is held to the platen carriage to travel therewith and is shiftable relatively to the carriage in the direction of the letter-spacing movement of the carriage, and also fore-and-aft of the machine. The denominational selector is 70 slidably held to a centering plate 52 by means of a pair of headed screws 53 which pass through an elongated slot 54 in the denominational selector and are threaded into the plate 52 substantially midway the length of said plate. The plate 52 is formed with elongated slots 54 at each end thereof and is shiftable held to a denominational selector actuating plate 55 by means of a 75 pair of headed screws 56 passing through the elongated slots 54 in the plate 52 and threaded into the denominational selector actuating plate 55. The denominational selector supporting and guiding plate 52 is normally centered relatively to the plate 55 by means of a pair of coil springs 57 connected at their inner ends to said plate 52 and at their outer ends to the plate 55. The denominational selector actuating plate 55 is 80 slidably held to the platen carriage to move relatively thereto in the direction of the letter-spacing movement of the carriage, by means of a pair of headed screws 59 passing through elongated slots 60 in the plate 55 and threaded into the rear transverse member of the platen carriage.

85 The denominational selector operating plate 55 is provided with a depending pin 58, the lower end of which engages in a 85 spiral groove 61 formed in a cylinder 62 held to a shaft 63 to rotate with said shaft and to slide longitudinally thereof. The opposite ends of the spirally grooved cylinder 62 are engaged by a pair of rear- 90

wardly extending brackets 64 rigidly held to the platen carriage 38 whereby said cylinder or sleeve 62 is adapted to be moved along the shaft 63 when the carriage is shifted in either direction of its travel. The pin 58 depending from the plate 55 is normally located at the right-hand end of the spiral groove 61 in the cylinder or sleeve 62, and the plate 55 is normally centered relatively to the platen carriage 38.

The denominational selector shifting plate 55 and the plate 52 and denominational selector 51 carried thereby are adapted to be shifted bodily and in unison with each other relatively to the carriage in the direction of the letter-spacing movement of the carriage, relatively different distances, through the instrumentality of a series of nine denominational-point selecting keys 65. Each of the denominational-point selecting keys 65 is supported on a vertically-reciprocable stem 66, passing through suitable apertures in a stepped finishing plate 67. Each key stem 66 is provided with a shoulder 68.

The shoulder 68 on the right-hand key stem 66 is located farthest from the lower end of the key stem and the shoulder on the left-hand key stem 66 is located nearest to the lower end of the key stem. All of the key stems are adapted to be depressed the same distance and are adapted to be returned to their normal positions by suitable spiral springs 69. The lower ends of the key stems 66 pass through suitable apertures in a rocking plate 70, and the shoulders 68 formed on the key stems are adapted to engage the upper surface of the plate adjacent the forward edge thereof and rock said plate relatively different distances about its pivot 71. The rear edge of the plate 70 is rigidly held to a bar 72 which is pivotally supported at its opposite ends on the pivot screws 71 which pass through a pair of oppositely disposed vertically extending plates

73 suitably supported in the main frame of the machine. The denominational-point-selecting keys 65 are provided with denominational indicating numerals 1, 10, 100, 1,000, 10,000, 100,000, 1,000,000, 10,000,000, and 100,000,000, progressively from right to left of the keyboard. The right-hand key 65 is adapted to rock the plate 70 to move the denominational selector 51 one letter space relatively to the carriage; the second key is

adapted to move the denominational selector two letter spaces, and the remaining keys are adapted to move the denominational selector progressively up to nine letter spaces. The plate 70 is formed at its forward edge with a finger 74 adjacent the right-hand end of the plate, adapted to engage and depress the upwardly turned forward end of a lever 75 which is pivotally supported intermediate its ends on the transverse pivot rod 14^b. The lever 75 and the

plate 70 are normally held in the positions shown in Fig. 1 by a suitable coil spring 76, and the depending rear end of the lever 75 is pivotally connected at 77 with the lower end of an upwardly extending lever 78. The lever 78 is formed at its upper end with a rack 79 meshing with a gear 80 fixed on the right-hand end of shaft 63, upon which the spirally grooved sleeve 62 is mounted. The upper end of the lever 78 is guided by a pin 81 passing through an elongated slot 82 in the upper end of the lever and held to the outer side of one of the brackets 83 in which the shaft 63 is journaled. It will be obvious that in whatever letter-spacing position the carriage may be the sleeve 62 may be rotated through the medium of any one of the keys 65 and the operating connections above described to shift the denominational selector the desired number of letter spaces relatively to the platen carriage to select the desired denominational point.

The denominational selector 51 is adapted to cooperate with any one of a series of column selecting stops 84, or with any one of a series of variably adjustable aligned tabulator stops 85 to select the desired denominational point within the columnar field of the stops. The column selecting stops and the adjustable tabulator stops are all normally out of the path of the denominational selector and are adapted to be moved independently into the path of the denominational selector through independent key-controlled mechanisms. The stops 85 are detachably and adjustably held to a notched tabulator-stop bar 86 in the usual manner. The tabulator-stop bar 86 is journaled at its left-hand end in one of the brackets 83, and is journaled at its right-hand end in a bracket 87, and is normally held in the position shown in Figs. 1, 2 and 5. The bar 86 is adapted to be rocked to move the depending ends of the tabulator stops downwardly and forwardly simultaneously into the path of one of the inclined faces 51^a formed on the denominational selector 51, by depressing the key 88 which is supported on the upper end of a vertically reciprocable key stem 89 passing through the plate 67 and pivotally connected at its lower end to the upwardly turned forward end of a lever 90. The lever 90 is pivotally hung intermediate its ends on the pivot rod 14^b, and is pivotally connected at its rear end with the lower end of an upwardly extending link 91. The link 91 is pivotally connected at its upper end with the lower end of an angular rock arm 92, the upper end of which is fixed on the left-hand end of the tabulator-stop bar 86. The key 88 and the operating connections between said key and the tabulator-stop bar are normally held in the positions shown in the drawings by means of a suit-

able coil spring 93 coiled about the key stem 89 and interposed between the key 88 and the plate 67.

The eight column-selecting stops 84 are held to a cylinder 94 fixed on a shaft 95 extending directly below the bar 86 and journaled at its opposite ends in the brackets 83. The cylinder 94 is of substantially the same length as the scale of the machine and the stops 84 are arranged in a spiral series about said cylinder. The stops 84 are spaced apart 40° circumferentially of the cylinder 94, and are spaced apart longitudinally of the cylinder a distance equal to ten letter spaces on a scale. The 80° space between the first and the last of the spiral series of stops 84 is normally at the upper side of the cylinder as shown in Fig. 5, thus providing an unobstructed passage for the downwardly and forwardly bent end of the denominational selector 51. The downwardly and forwardly bent end of the denominational selector is formed with inclined faces 51^b adapted to engage a column selecting stop when the cylinder 94 is rotated to present one of said stops in the path of the denominational selector. The cylinder 94 is adapted to be rotated relatively different distances to present any desired column-selecting stop 84 in the path of the denominational selector, through the medium of a series of eight keys 96. Each of the keys 96 is supported on a key stem 97 passing through apertures in the plate 67 and in the forward edge of a rocking plate 98. The key stems 97 are formed with shoulders 99 similar to the shoulders 68 on the key stems 66, the shoulder 99 on the right-hand key stem 97 being farthest from the plate 98, and the shoulder 99 on the left-hand key stem 97 being nearest to the plate 98. The key stems are normally held in the positions shown in Figs. 1 and 8 by suitable coil springs 100 coiled about the key stems 97 and interposed between the keys 96 and the plate 67. The plate 98 is held at its rear edge to a bar 101 which is pivotally held at its ends to the plate 73 by pivot screws 102. Plate 98 is provided at its right-hand end adjacent its forward edge with a depending finger 103 engaging the upwardly turned end of a lever 104 pivotally hung on the transverse pivot rod 105 and normally held in the position shown in the drawings by means of a suitable spring similar to the spring 76 connected with the lever 75. The downwardly turned rear end of the lever 104 is pivotally connected with the lower end of an upwardly extending lever 106 which is formed at its upper end with a rack 107 meshing with a gear 108 fixed on the shaft 95, upon which the cylinder 94 is mounted. The upper end of the lever 106 is formed with an elongated slot 109 through which the shaft 95 extends, whereby the upper end of the lever 106 is guided and the

rack 107 is held in mesh with the gear 108. The keys 96 are marked with suitable indicating numerals corresponding to points on the scale of the machine, such as 10, 20, 30, 40, 50, 60, 70 and 80, and the first stop of the series of column-selecting stops 84 is so located on the cylinder as to engage the denominational selector and arrest the carriage at the point 10 on the scale of the machine when the right-hand column-selecting stop key 96 is depressed. It will be obvious that by pressing the selected key 96 the plate 98 will be rocked a sufficient distance to rotate the cylinder 94 and present the desired column-selecting stop 84 in the path of one of the inclined faces 51^b formed on the denominational selector.

When one of the inclined faces 51^a or 51^b of the denominational selector 51 engages a tabulator stop 85 or a column-selecting stop 84, it will be obvious that a slight additional movement of the carriage under the influence of the power driving mechanism heretofore described will force the denominational selector in the direction of the movement of the carriage relatively to the engaged stop, whereupon the selector will be shifted bodily forwardly of the machine, owing to the cam action between the inclined face thereof and the engaged stop. This forward movement of the denominational selector 51 will force the dog 110, formed on the forward end of the denominational selector, between the two adjacent teeth 111 formed on the plate 47, thus locking the plate 47 against further movement with the platen carriage, owing to the engagement of one of the straight faces 51^c of the rear end of the denominational selector with the stop. Owing to the pin-and-slot connections 48 and 49 between the plate 47 and the platen carriage 38, it will be observed that the platen carriage may continue to move under the influence of the power driving mechanism for a short distance after the denominational selector has locked the plate 47 against further movement in unison with the carriage. This relative movement between the platen carriage and the plate 47 causes a relative movement between the traveling carriage-arresting stop 42 and the depending arms 45 and 46 formed on the plate 47, causing the pin 44 on the stop 42 to engage either the stop face 45^a on the arm 45 or the stop face 46^a on the arm 46, according to the direction of movement of the carriage, thus rocking the stop on its pivot 43 and moving the projection 42^a or the projection 42^b, as the case may be, into engagement with the stationary rack 41 and locking the carriage against further movement under the influence of the power driving mechanism.

When a column-selecting stop or a tabulator stop is engaged by the denominational

selector without previously depressing one of the denominational selecting keys 65, the dog 110 on the denominational selector is adapted to engage between the two right-hand teeth on the plate 47, and when the right-hand or units denominational selecting key is depressed the dog 110 is adapted to engage between the second and third teeth on the plate 47, and when the left-hand denominational-point-selecting key is depressed the dog 110 is adapted to engage between the tenth and eleventh teeth on the plate 47, or nine letter spaces from the decimal point.

15 Extending transversely of the machine in front of the carriage is a rock shaft 112 journalled at its opposite ends in suitable supports 113 held to the main frame of the machine. A sleeve 114 is mounted on the rock shaft 112 to rock with said shaft and to slide longitudinally thereof, said sleeve carrying a key or fin 115 engaging in a longitudinally extending groove 116 formed in the shaft 112. The sleeve 114 is adjustable longitudinally on shaft 112 through a marginal-point indicator 117 held to said sleeve to move transversely of the machine therewith and to rotate relatively thereto. The marginal-point indicator 117 is formed with a pointer 118 adapted to move over the face of the letter-space scale plate 119 which is held to the supports or brackets 113. The marginal indicator 117 is also formed with a stop face 120 adapted to engage between teeth or notches 121 formed on the lower edge of the scale plate and registering with the graduations of the scale, said indicator 117 being normally forced upwardly to hold the stop face 120 in engagement with said teeth 121, by means of a suitable spring 122 held to the sleeve 114. The sleeve 114 is formed with a rearwardly extending arm 123, the free end of which is formed with a laterally extending inclined portion 124 lying in the path of a roller 125 held to the front transverse bar 38^a of the platen carriage 38, substantially midway the length thereof. The roller 125 travels along a transversely extending track 126 held to the supports 113, and is adapted to engage the inclined face 124 on the arm 123 as the carriage approaches the end of its return movement and to thus depress said arm and rock the shaft 112. A rock arm 127 is rigidly held to the shaft 112 adjacent the right-hand end of said shaft, and the lower end of said rock arm is pivotally connected with the forward end of a horizontal rearwardly extending link 128 which is pivotally connected at its rear end with an upwardly extending rod or arm 129. The upper end of the rod 129 is secured to the rear edge of a rocking plate 130. The plate 130 is formed at its opposite ends adjacent its rear edge, with ears 131, and is pivotally supported on the brackets 83 by suitable pins 132 extending through said brackets and through the ears 131. The plate 130 is formed with a rack 133 at its forward edge, and it will be obvious that when the arm 123 is depressed by the roller 125 said rack 133 will be moved upwardly, thus causing a depending tooth 134 formed on the depending arm 46 on the carriage-arresting-stop-actuating plate 47 to engage between adjacent teeth on the rack 133, thereby locking the plate 47 against further movement with the platen carriage. It will be obvious that when the plate 47 is locked against movement by the rack 133, a further return movement of the carriage will cause the stop face 45^a to engage the pin 44 on the carriage-arresting stop 42 and rock the dog 42^a into engagement with the stationary rack 41, thus arresting the carriage at the selected marginal point.

50 What I claim is:

1. In a typewriting machine, the combination of a platen carriage, a denominational selector shiftably mounted on the carriage, key-controlled means for shifting the selector relatively to the carriage in the direction of the letter-spacing movement thereof a distance equal to one or more letter spaces, a series of aligned stops supported independently of the carriage and adjustable relatively to each other longitudinally of the path of movement of the carriage, a second series of uniformly spaced stops arranged fixed distances apart longitudinally of the path of movement of the carriage, a key operatively connected to shift the first series of stops simultaneously into the path of movement of the denominational selector, independent key-operated means for selectively positioning either of the second series of stops in the path of the denominational selector, a rack supported independently of the carriage, and a carriage-arresting stop movable through the instrumentality of the denominational selector into engagement with the rack upon engagement of the selector with any stop of either series of stops.

55 2. In a typewriting machine, the combination with a platen carriage, of means for moving the same continuously a plurality of letter spaces, a denominational selector shiftably mounted on the carriage, key-operated means for advancing the selector relatively to the carriage a desired number of letter spaces, a series of adjustable aligned tabulator stops normally out of the path of said selector, means for shifting said stops simultaneously into the path of movement of the selector, a series of column-selecting stops spaced uniform distances apart, means for presenting either of said uniformly spaced stops in the path of the selector, and means operatively connected with the selector for arresting the carriage

upon engagement of the selector with a stop of either series.

3. In a tabulating mechanism for a writing machine having a traveling paper carriage, the combination of column-point determining means and denominational-order determining means arranged to be interengaged by traveling movement of the carriage, denominational keys for moving the 10 denominational-order determining means longitudinally of the path of travel of the carriage varying distances in accordance with the value of the key actuated, and means put into action by interengagement 15 of the column-point determining means and denominational-order determining means for arresting the carriage.

4. Tabulating mechanism for typewriting machines, comprising a platen carriage, a 20 denominational-point determining device mounted on the carriage to travel therewith, a series of keys operatively connected to advance said device relatively to the carriage varying numbers of letter spaces, a 25 series of stops settable different numbers of letter spaces apart, a second series of stops spaced equal numbers of letter spaces apart, means for simultaneously shifting the first series of stops into and out of the path of 30 said device, a series of stop-selecting keys operatively connected with the second series of stops to position either of said stops in the path of said device, and means operable by the denominational-point determining 35 device for arresting the carriage upon engagement of the device with a stop of either series.

5. Tabulating mechanism for typewriting machines, comprising a platen carriage, a 40 denominational-point determining device mounted on the carriage to travel therewith, a series of keys operatively connected to advance said device relatively to the carriage varying numbers of letter spaces, a series 45 of stops settable different numbers of letter spaces apart, a second series of stops spaced equal numbers of letter spaces apart, means for simultaneously shifting the first series of stops into and out of the path of said device, a series of stop-selecting keys operatively connected with the second series of 50 stops to position either of said stops in the path of said device, means operable by the denominational-point determining device for arresting the carriage upon engagement 55 of the device with a stop of either series, power mechanism for moving the carriage in either direction, and key-operated means for releasing the carriage and causing said 60 power mechanism to drive the carriage in the proper direction to the selected point.

6. In a typewriting machine, the combination of a frame, a platen carriage movable transversely of the frame, key-controlled 65 power-operated means for driving the car-

riage continuously through a plurality of letter spaces in either direction, a denominational-point determining device movable with the carriage, means for selectively advancing said device one or more letter 70 spaces relatively to the carriage, a series of relatively adjustable tabulator stops supported independently of the carriage, means for simultaneously shifting said stops into and out of the path of said device, and carriage-arresting means operable by said device when the device strikes a stop.

7. In a typewriting machine, the combination of a frame, a platen carriage movable transversely of the frame, key-controlled 80 power-operated means for driving the carriage continuously through a plurality of letter spaces in either direction, a denominational-point determining device movable with the carriage, means for selectively advancing said device one or more letter spaces 85 relatively to the carriage, a series of selectively settable stops spaced an equal number of letter spaces apart, key-operated means for setting any desired one of said stops in the path of the denominational-point determining device, and carriage-arresting means operable by said device when the device strikes a stop.

8. In a typewriting machine, the combination of a platen carriage and tabulating mechanism associated with the carriage, said mechanism comprising a key-set denominational-point selector mounted on the carriage, a shiftable carriage-arresting stop 100 mounted on the carriage, a series of relatively adjustable tabulator stops mounted independently of the carriage, means for shifting the tabulator stops simultaneously into and out of the path of said selector, a 105 rack supported independently of the carriage, and means connecting said carriage-arresting stop and selector for moving the stop into engagement with the rack when the selector strikes a tabulator stop.

9. In a typewriting machine, the combination of a platen carriage and tabulating mechanism associated with the carriage, said mechanism comprising a key-set denominational-point selector mounted on the carriage, a shiftable carriage-arresting stop mounted on the carriage, a series of column selecting stops spaced ten letter spaces apart, key-operated means for setting any desired 115 one of said stops in the path of said denominational-point selector, and connections between the selector and carriage-arresting stop for actuating said carriage-arresting stop when the selector engages a set stop.

10. In a typewriting machine, the combination of a frame, a carriage movable transversely of the frame, key-controlled power-operated means for driving the carriage in either direction transversely of the frame to a selected point, independently adjustable 120

tabulator stops, column selecting stops, an adjustable margin-determining device, and carriage-arresting means adapted to cooperate with either the tabulator stops, column 5 selecting stops, or margin-determining device.

11. In a typewriting machine, the combination of a platen carriage, a stationary rack, a shiftable carriage-arresting stop 10 mounted on the carriage, column selecting stops mounted independently of the carriage, a series of denomination selecting keys, a device mounted on the carriage and shiftable endwise of the carriage by said 15 keys and in a different direction by the column selecting stops, means for setting a selected column stop in the path of said device, and means connecting said device with the carriage-arresting stop for shifting the 20 arresting stop into engagement with the rack when said device strikes a set column selecting stop.

12. In a tabulating mechanism for a writing machine having a traveling paper carriage, the combination of key-set denominational-order determining means yieldably held in normal position and movable by the keys different distances in one direction from normal position longitudinally of 25 the path of the carriage, a plurality of column-point determining abutment devices, and a universal carriage-arresting stop actuated to arrest the carriage upon engagement of the denominational-order determining 30 means and either of said abutment devices with each other effected by a running movement of the carriage.

13. In a typewriting machine, the combination of a frame, a carriage movable 40 transversely of the frame, a stationary rack supported on the frame, a carriage-arresting stop mounted on the carriage and adapted to engage said rack, key-controlled column selecting stops, a tabulator-stop bar, adjustable tabulator stops carried by said bar, key-controlled means for shifting said bar, an adjustable carriage-operated margin-determining device, and means whereby said carriage-arresting stop may be moved into 45 engagement with said rack through the instrumentality of either a column selecting stop, tabulator stop, or the margin-determining device.

14. In a typewriting machine, the combination of a series of relatively adjustable tabulator stops, a shiftable support for said tabulator stops, a series of uniformly spaced column selecting stops, a platen carriage movable longitudinally of the two series of 50 stops, a single denominational selector mounted on the carriage, a series of keys operatively connected to shift the selector different distances relatively to the carriage 55 longitudinally of the two series of stops, a key connected with the tabulator stop sup-

port for shifting the tabulator stops simultaneously into and out of the path of the selector, a series of keys connected with the column selecting stops for moving any desired column selecting stop into the path 70 of the selector, and means operable by the selector upon engagement with a stop of either series for arresting the carriage.

15. In a typewriting machine, the combination of a series of relatively adjustable tabulator stops, a shiftable support for said tabulator stops, a series of uniformly spaced column selecting stops, a platen carriage movable longitudinally of the two series of stops, a single denominational selector 75 mounted on the carriage, a series of keys operatively connected to shift the selector different distances relatively to the carriage longitudinally of the two series of stops, a key connected with the tabulator stop support for shifting the tabulator stops simultaneously into and out of the path of the selector, a series of keys connected with the column selecting stops for moving any desired column selecting stop into the path 80 of the selector, key-controlled power mechanism for driving the carriage in either direction, and means operable by the selector irrespective of the direction of movement of the carriage for arresting the carriage 85 upon engagement of the selector with any stop of either series.

16. In a typewriting machine, the combination of a platen carriage, a series of variably adjustable tabulator stops, a series 100 of uniformly spaced selectively settable column stops, a single denominational-point determining device mounted on the carriage, means for shifting said device different distances longitudinally of the carriage, and carriage-arresting means operable by said device upon engagement of the device with a tabulator stop or column stop. 105

17. In a typewriting machine, the combination of a platen carriage, a series of 110 variably adjustable tabulator stops, a series of column selecting stops, a denominational point determining device mounted on the carriage and shiftable longitudinally and transversely relatively thereto, means for simultaneously shifting the tabulator stops into the path of said device, means for shifting any desired column selecting stop into the path of said device, said device having cam surfaces at opposite sides thereof 115 for causing the device to move transversely of the carriage upon engagement of the device with a stop of either series, means operable by said device for arresting the carriage when said device is moved transversely 120 of the carriage, and power means for moving the carriage in either direction to the selected point. 125

18. In a typewriting machine, the combination of a platen carriage, a denomina- 130

- tional selector mounted on the carriage, means for shifting the selector different distances longitudinally of the carriage, a series of stops supported independently of the carriage, and means operable by the selector for arresting the carriage upon engagement of the selector with a stop. 5
19. In a typewriting machine, the combination of a platen carriage, a denominational selector having cam surfaces at opposite sides thereof mounted on the carriage to slide endwise transversely of the carriage, means for shifting the selector sidewise different distances longitudinally of the carriage, a series of column selecting stops mounted independently of the carriage movable into and out of the path of said selector, a carriage-arresting stop pivotally held to the carriage having stop dogs at opposite sides of its pivot, a stationary rack, and means on the carriage for rocking the stop to cause one or the other of said dogs to engage the rack when the selector is moved endwise by the engagement of one of the cam surfaces thereon with a column selecting stop. 10
20. In a typewriting machine, the combination of a platen carriage, a denominational selector having cam surfaces at opposite sides thereof mounted on the carriage to slide endwise transversely of the carriage, means for shifting the selector sidewise different distances longitudinally of the carriage, a series of column selecting stops mounted independently of the carriage movable into and out of the path of said selector, a carriage-arresting stop pivotally held to the carriage having stop dogs at opposite sides of its pivot, a stationary rack, and means on the carriage for rocking the stop to cause one or the other of said dogs to engage the rack when the selector is moved endwise by the engagement of one of the cam surfaces thereon with a column selecting stop. 15
21. In a typewriting machine, the combination of a platen carriage, a denominational selector mounted on the carriage, means for shifting the selector different distances longitudinally of the carriage, a series of column selecting stops, means for setting any desired stop in the path of the selector, power means for moving the carriage at a single run from any position until the selector engages a set stop, and means operable upon engagement of the selector with a stop for arresting the carriage. 20
22. In a typewriting machine, the combination of a platen carriage, a series of stops mounted independently of the carriage, a selectively settable denominational-point determining device mounted on the carriage, and means operable by the selector mounted on the carriage, means for shifting the selector different distances longitudinally of the carriage, a series of stops supported independently of the carriage, and means upon engagement thereof with one of said stops, and marginal-point determining means also adapted to actuate said carriage-arresting means. 25
23. In a typewriting machine, the combination of a platen carriage, a series of column selecting stops mounted independently of the carriage, a selectively settable denominational-point determining device mounted on the carriage adapted to engage a set stop, an adjustable marginal-point determining trip operable by the carriage, and a single carriage-arresting means controlled by both of said devices. 70
24. In a typewriting machine, the combination of a platen carriage, a series of column selecting stops mounted independently of the carriage, a selectively settable denominational-point determining device mounted on the carriage adapted to engage a set stop, an adjustable marginal-point determining trip operable by the carriage, a stationary rack supported independently of the carriage, and a carriage-arresting stop mounted on the carriage shiftable into engagement with said rack through the instrumentality of either of said devices. 80
25. In a typewriting machine, the combination of a platen carriage, a stationary rack supported independently of the carriage, a carriage-arresting stop mounted on the carriage adapted to engage said rack, tabulating-point selecting means cooperating with said stop to arrest the carriage, and marginal-point determining means cooperating with said stop to arrest the carriage. 85
26. In a typewriting machine, the combination of a carriage, a fixed rack, a carriage-arresting stop traveling with the carriage adapted to engage said rack, tabulator mechanism adapted to actuate said stop, and an adjustable carriage-operated trip device operatively connected to actuate said carriage-arresting stop when the carriage is returned to the marginal point for which said trip device is set. 95
27. In a typewriting machine, the combination of a platen carriage, a stationary rack, a stop traveling with the carriage adapted to engage said rack, a marginal-point indicator adjustable transversely of the machine, a trip operable by the carriage and adjustable with said indicator, tabulating-point selecting means, and means whereby said stop may be moved into engagement with the rack through the instrumentality of either the trip or the tabulating-point selecting means. 100
28. In a tabulating mechanism for a writing machine having a traveling paper carriage, the combination of a series of column-point determining abutment devices mounted on the machine frame, a single denominational-order determining abutment device movable with the carriage, denominational 115
- carriage-arresting means operable by said 120
- 65 125
- carriage-arresting means operable by said 130

tional-order keys on the machine frame connected to shift said denominational-order abutment device longitudinally of the path of the carriage different distances, and a 5 series of independently operable column-selecting keys on the machine frame operatively connected to shift different ones of said series of column-point determining abutment devices into position to be engaged 10 by said single abutment device on the carriage to effect stopping of the carriage.

29. In a typewriting machine, the combination of a frame, a platen carriage movable transversely of the frame, key-controlled power-operated means for driving the carriage in either direction transversely of the frame, column selecting stops, and carriage-arresting means embodying a single denominational-point selecting device movable with the carriage into engagement with any one of said stops and adjustable relatively to the carriage longitudinally of the carriage.

30. In a typewriting machine, the combination of a platen carriage, a rotatable carrier, a series of column selecting stops spaced around said carrier and longitudinally thereof, a denominational selector on the carriage, key-actuated means for moving the said selector transversely of the machine, key-actuated means for rotating the stop carrier to bring a selected stop into the path of the denominational selector, and means actuated by the selector for arresting 35 the carriage when said selector engages a column selecting stop.

31. Mechanism for arresting the carriage of a typewriting machine at predetermined points, comprising a stop traveling with 40 the carriage, a stationary rack, a denominational selector traveling with the carriage, means for shifting said denominational selector in the direction of the carriage movement to select a denominational point, column selecting stops, means for shifting any desired one of said column selecting stops into the path of the denominational selector, and connections between the carriage stop and the denominational selector for shifting 45 the carriage stop into engagement with said stationary rack.

32. In a typewriting machine, the combination of a frame, a stationary rack, a platen carriage mounted on the frame, a 55 carriage-arresting stop mounted on the carriage and adapted to engage the rack, a denominational selector mounted on the carriage, key-controlled means for shifting the denominational selector relatively to the 60 carriage in the direction of the letter-spacing movement thereof, column selecting stops, key-controlled means for moving one of said denominational stops into the path of the denominational selector, means for 65 shifting said carriage-arresting stop into

engagement with the stationary rack when the denominational selector engages a column selecting stop, and key-controlled means for moving the carriage to the selected point.

33. In a typewriting machine, a carriage-arresting stop, a denominational-selecting mechanism adapted to actuate said stop to arrest the carriage at different denominational points, a rotatable shaft provided 70 with a series of column-selecting stops each of which is adapted to strike against and actuate said denominational-selecting mechanism, a plurality of keys for adjusting said shaft, and a rockable bar carrying a series of adjustable tabulating-stops each of which is also adapted to cooperate with said denominational-selecting mechanism to arrest the carriage independently of said column-selecting stops, for the purpose set 75 80 forth.

34. In a tabulating mechanism for a writing machine having a traveling paper carriage, the combination of a series of column-point abutment devices, a denominational-order determining abutment device, means for shifting said denominational-order determining abutment device longitudinally of the path of travel of the carriage to different denominational-order positions, means whereby said denominational-order determining device may be brought into engagement with a column-point abutment device and then shifted transversely of the path of the carriage when the carriage is given a running movement, and means put into action by said movement of the denominational-order determining device transversely of the path of the carriage for stopping the carriage.

35. In a tabulating mechanism for a writing machine having a traveling paper carriage, the combination of means for running the carriage by power from any letter-space position in its travel directly in one direction to any other letter-space position, said means embodying selectively settable column-point determining devices on the machine frame and means mounted on the carriage to travel therewith until arrested by engagement with one side or the other of a set column-point determining device, said means on the carriage being selectively movable independently of the carriage longitudinally of the path of the carriage different distances in one direction and being movable transversely of the path of travel of the carriage by the set column-point determining device to effect stopping of the carriage in the selected letter-space position.

36. In a tabulating mechanism for a writing machine having a traveling paper carriage, the combination of an abutment device on the machine frame, an abutment device on the carriage adapted to engage against 125 130 135

- either side of the device on the frame to effect stoppage of the carriage when moving in either direction, denominational key-actuated means for shifting said abutment 5
 5 device on the carriage different distances relatively to the carriage longitudinally of the path of travel of the carriage, means whereby the carriage may continue to travel a short distance after engagement of said 10
 10 devices when moving in either direction, and carriage-stopping means operable by said continued movement of the carriage to stop the carriage at the selected tabulating point.
37. In a typewriting machine, a rockable 15 carriage-stop on the carriage having two opposite stop-dogs, a rack on the frame, means for giving the carriage a running movement in either direction, a series of stops, and means actuatable by any one of said stops for 20
 20 rocking the carriage-stop in either direction to stop the carriage by engagement with said rack, said means embodying a denominational selector adapted to move transversely of the carriage to put said carriage stop 25
 25 into action and movable longitudinally of the carriage to determine the denominational position within the field of the engaged one of said series of stops at which the carriage will be arrested.
38. In a typewriting machine, a rockable carriage-stop on the carriage having two opposite stop-dogs, a rack on the frame, means for giving the carriage a running movement in either direction, a series of 35
 35 stops, and means actuatable by any one of said stops for rocking the carriage-stop in either direction to stop the carriage by engagement with said rack, said means embodying a denominational selector adapted 40
 40 to move transversely of the carriage as well as longitudinally thereof, and a toothed resiliently-held plate adapted to be engaged by the selector and carrying means for rocking said carriage-stop.
- 45 39. In a typewriting machine, a combina-
 tion of a paper carriage, a universal carriage-stop on the carriage, a rack on the machine frame engageable by said universal stop, column-point determining means on the frame, denominational-order determin- 50
 50 ing means on the carriage adapted to engage the column-point determining means and be actuated by such engagement to put the universal stop into action, and means for adjusting the denominational-order determining means longitudinally of the path of the carriage and independently of movement of the carriage to different denominational-order positions.
40. In a tabulating mechanism for writing machines having a traveling paper carriage, the combination of a stationary stopping rack, a universal carriage stop on the carriage engageable with said rack, a laterally yieldable member on the carriage 60
 60 adapted to throw said stop into engagement with the rack, a laterally yieldable and fore-and-aft shiftable abutment device on the carriage, and a cooperating non-traveling abutment device adapted to arrest traveling movements of the yieldable abutment device and shift said yieldable abutment device in a fore-and-aft direction into interlocking engagement with the laterally yieldable actuating member for the universal 65
 65 carriage stop.
41. In a typewriting machine, a double-dog rockable stop on the carriage and means for rocking the same in either direction, and a stop-rack on the frame extending the length of travel of the carriage, said means embodying a member on the carriage adapted 70
 70 to slide in either direction to rock the stop in either direction and also a movable rack extending the length of travel of the carriage and adapted to engage said member.
- This specification signed this twenty-seventh day of June, A. D. 1918.

MANSFIELD C. CRAWLEY.
